Inventor,
Adolph Dietzsche, Jr.;
By Wilbur M. Stone
his Attorney.

UNITED STATES PATENT OFFICE.

ADOLPH DIETSCHÉ, JR., OF NEW YORK, N. Y., ASSIGNOR TO AMERICAN LITHOGRAPHIC COMPANY, OF NEW YORK, N. Y., A CORPORATION OF NEW YORK.

DISPLAY DEVICE.

Application filed June 28, 1922. Serial No. 571,550.

To all whom it may concern:

Be it known that I, ADOLPH DIETSCHÉ, Junior, a citizen of the United States, and a resident of New York, borough of Queens, 5 in the county of Queens and State of New York, have invented certain new and useful Improvements in Display Devices, of which the following is a specification.

This invention relates to display devices 10 and particularly to that class thereof which is formed of sheet material and adapted to display articles of merchandise resting thereon. The object of my improvements is to provide a device of the class specified, 15 simple in construction and economical of manufacture, and which may be laid flat for purposes of shipment.

With these ends in view my improvements 20 comprise features illustrated in their preferred embodiment in the drawing accompanying this specification, wherein:

Figure 1 is a perspective view of my improved device in erected position. Fig. 2 25 is a plan view of the blank, cut and scored, ready for folding and erection. The two views are to the same scale.

Referring now to the drawing, upstanding wall 2 is the principal member of the 30 device and the face thereof may carry printed matter relating to the articles displayed. Said wall 2 is provided with opposite downwardly reaching legs 3, 4 having articulated to their inner edges 5, 6, respectively, rearwardly extending wings 7, 8. To 35 the bottom edges 9, 10, of said wings, respectively, are articulated inwardly extending base portions 11, 12. The inreaching edges of said base portions are adapted to abut one another, thus maintaining said wings in rearwardly extended positions and the entire device in erected position.

When the device is in erected position, 40 said base portions 11, 12 may receive resting thereon and within the opening between said edges 5, 6 of legs 3, 4, respectively, any article of merchandise which it is desired to display.

It will thus be seen that my improved device is adapted to be integrally cut from a 45 single piece of suitable sheet material, such as card-board or the like, and to be self-sustaining upon erection without fastening

means other than that inherent in folding the device into display position.

I claim:

1. In a display device of sheet material the combination of an upstanding wall having opposite downwardly reaching legs, a wing articulated to the inner edge of each of said legs, and a base portion articulated 55 to the bottom edge of each of said wings.

2. In a display device of sheet material the combination of an upstanding wall having opposite downwardly reaching legs, a rearwardly extending wing articulated to 60 the inner edge of each of said legs, and an inwardly extending base portion articulated to the bottom edge of each of said wings.

3. In a display device of sheet material the combination of an upstanding wall having opposite downwardly reaching legs, a rearwardly extending wing articulated to 65 the inner edge of each of said legs, and an inwardly extending base portion articulated to the bottom edge of each of said wings, 70 said base portions having their inreaching edges adapted to abut one another whereby said wings are maintained in rearwardly extending positions respectively.

4. In a display device of sheet material 75 the combination of an upstanding wall having opposite downwardly reaching legs, a wing articulated to the inner edge of each of each of said legs, and a base portion articulated to the bottom edge of each of said wings, 80 said base portions each having a width greater than the width of said wings respectively.

5. In a display device of sheet material 85 the combination of an upstanding wall having opposite downwardly reaching legs, a rearwardly extending wing articulated to 90 the inner edge of each of said legs, and an inwardly extending base portion articulated to the bottom edge of each of said wings, 95 said base portions extending forwardly of said upstanding wall and having their inreaching edges adapted to abut one another whereby said wings are maintained in rearwardly extending positions respectively. 100

In witness whereof, I hereby affix my signature this 26 day of June, 1922.

ADOLPH DIETSCHÉ, JR.
